SLIDING DOOR

Arthur Thomas Charles Burrows, Hitchin, England, assignor to Geo. W. King Limited, Hitchin, England, a British company

Application January 10, 1951, Serial No. 205,286
In Great Britain September 29, 1948

6 Claims. (Cl. 20—19.)

1

This invention relates to sliding doors and has among its objects to evolve an arrangement whereby such a door, on being moved into its closed position, may be caused positively to press or bear against resilient sealing strips or equivalent sealing means disposed around the door opening and thereby to produce an effective seal.

In accordance with the invention a sliding door which is adapted to be moved back and forth in a predetermined path into and away from its closed position has means associated therewith which are adapted to impart a vertical movement to the door subsequent to its arrival in the closed position and a reverse vertical movement prior to its removal from such position, such vertical movements of said door being utilised to effect operation of pivoted latch or hook members which are disposed at two opposed lateral edges of the door and are adapted to cooperate with fixed brackets located at either side of the door opening in such a manner that, dependent upon the direction of vertical movement of the door, the latch or hook members will co-operate with the brackets to move said door either bodily inwardly against or outwardly from sealing means disposed around the door opening.

In order that the invention may be clearly understood and readily carried into effect the same will be hereinafter more fully described with reference to the accompanying drawings in which:

Figure 1 is a front elevational view of a sliding door and operating mechanism therefor according to the invention;

Figures 2 and 3 are end elevational views of the arrangement shown in Figure 1, Figure 2 showing the upper part of the door and its associated mechanism and Figure 3 showing the lower part;

Figure 4 is a plan view of the door the upper part incorporating the operating mechanism having been removed.

Figure 5 is an end elevational view of the upper part of the door and its associated mechanism and illustrates clearly the relative position of the parts immediately prior to sealing of the door; and

Figure 6 shows a detail of construction on a larger scale.

Referring to the drawings 10 denotes a door which may comprise any suitable rigid panel-like structure and is capable of being moved along a predetermined path from an open to a closed position and vice versa. In the embodiment illustrated the door 10 is suspended from two trolleys 11 which are adapted to run on a fixed overhead track 12 disposed above the door opening. One

2

or both of the trolleys 11 may conveniently be power operated in order that the door may be driven into or out of its closed position as desired. Associated with the door 10 is a lifting unit 13 comprising an electric motor 13 which is coupled, through the medium of a fluid coupling and suitable gearing, to a threaded rod 14 rotatably journalled within the door structure in such a manner that its longitudinal axis is vertical or substantially so. Mounted on the threaded rod 14 is a correspondingly threaded member 15 in the form of a nut or equivalent device which is normally restrained against rotation and is further adapted, on rotation of said rod 14, to be moved vertically upwardly or downwardly relatively to the latter. Attached to the threaded member 15, which may be constrained to move in suitable guides, is a pair of ropes or cables 16 each of which is adapted to pass from said member around a suitable sheave or pulley 17 freely mounted at the upper part of the door and thence around a sheave 18 carried by the appropriate trolley 11, the ends of the two ropes being coupled together through the medium of a turn buckle 19 which allows for adjustment of said ropes. The sheaves or pulleys 17 are spaced equidistantly from the vertical centre line of the door at opposite sides of the latter the arrangement being such that when the threaded member 15 is moved 20 upwardly due to rotation of the threaded rod 14 in the appropriate direction the door 10 will be lifted relatively to the fixed track while, when said member 15 is moved downwardly, a corresponding downward movement of the door 10 will 25 result. The arrangement is such that when, for example, the door is to be moved from the closed to the open position the motor 13 will be operated initially to effect lifting of said door through a predetermined distance whereafter it will be 30 switched off automatically in any convenient manner and the power operated trolley or trolleys 11 will be set in operation to drive the door 10 along the track 12 into its open position. On closing the door 10 a drive is imparted to the power operated trolley or trolleys 11 to move 35 the door into the door opening. When the door 10 reaches the closed position the arrangement is such that the drive to the trolleys 11 will be automatically discontinued while the motor 13 will be operated automatically to drive the 40 threaded rod 14 in such a direction as to result in lowering of the door. It is only intended that the door shall be raised or lowered prior to each 45 opening or closing movement by a comparatively small amount, for example, in the region of two 50 inches or thereabouts.

When the door is at rest the tension on both of the suspension ropes 16 will be equalised and the correct setting of the door may be obtained by adjusting the length of said ropes through the medium of the turn buckle 19. When the length of the ropes has been so adjusted, lock nuts 20 on either side of the turn buckle may be set to co-operate with cleats 21 mounted on the tie bars 22 thereby to maintain such adjustment. This arrangement, besides allowing for adjustment of the door, will also prevent rocking thereof during traverse movement.

The raising or lowering movement of the door 10 above described is utilised to effect or control the sealing of the latter when in its closed position as will now be more fully described. Disposed adjacent and parallel to each lateral edge of the door is a bar or rod 23 which is formed with a plurality of latch or hook elements 24 at spaced points therealong. Each bar 23 is connected to the appropriate lateral edge of the door through the medium of two or more pivoted links 25 so that it will be capable of parallel movement relatively to the door edge. In the embodiment illustrated, as will be seen from Figures 2 and 3, the bars 23 at the opposite sides or edges of the door are slightly offset with respect to each other, that shown in dotted lines at the trailing edge being so arranged that the latch or hook elements 24 thereon will project a greater distance beyond the rear face of the door than the latch or hook elements 24 carried by the bar 23 at the leading edge. Preferably, the bar or rod 23 at each side of the door is provided with a roller 26 at its lower end which is adapted to engage in a groove or channel running across the lower part of the door opening the arrangement being such that while the bars or rods 23 will travel with the door when the latter is driven along the track they will not be subjected to any vertical lifting movement corresponding to that imparted to the doors. Suitably disposed at either side of the door opening are brackets or the like 27 with each of which one of the latch or hook elements 24 associated with the bars 23 is adapted to engage as the door is moved into its closed position, the arrangement being such that as the door is moved into its closed position by means of the drive imparted to the trolleys 11 the latch or hook elements 24 at each edge thereof will be brought into engagement with the appropriate brackets 27 which are fixedly mounted and on subsequent downward movement of the door and consequent relative movement of said bars said door will be forced bodily inwardly against resilient sealing strips 28 disposed around the door opening. It will be appreciated that as the bars or rods 23 are maintained in one vertical plane and are not subjected to any raising or lowering movement corresponding to that imparted to the door a toggle like action will be provided by said bars or rods and the latch or hook elements 24 which, owing to the engagement of said latch or hook elements with the fixed brackets 27, will cause the door to be moved bodily inwardly or outwardly with respect to the plane of the door opening. On lifting the door prior to opening movement thereof the latch or hook elements 24 will be effective to force the door away from the sealing devices whereafter it may be driven into the open position on operation of the trolleys 11.

I claim:

1. A sliding door assembly comprising a door movable horizontally back and forth along a pre-

determined path into and out of a closed position in front of and registering with a door opening, means connected to said door and operative to effect a downward vertical movement of said door subsequent to the arrival of the latter at said closed position and an upward vertical movement of said door prior to the removal of the latter from said closed position, a bar element disposed adjacent each of the vertical leading and trailing edges of said door and extending parallel to said edges, at least two link elements pivotally connected to each of said bar elements and the adjacent vertical edge of said door and swingable about axes parallel to the plane of said door so that vertical movement of said door relative to said bar elements is accompanied by relative movement of said door and bar elements in the direction normal to said plane of the door, latch elements projecting rearwardly from said bar elements, sealing means facing forwardly around the door opening, and keeper brackets fixedly disposed at each side of the door opening, said keeper brackets opening to one side to receive said latch elements therein when said door is moved to its closed position and prevent downward movement of said bar elements relative to said keeper brackets so that, when said door is moved vertically downward after arrival at said closed position, said door is displaced rearwardly into engagement with said sealing means around the door opening.

2. A sliding door assembly according to claim 1; further comprising a track member extending along the lower edge of the door opening, and a roller on the lower end of each of said bar elements engaging said track member to prevent movement of said bar elements in the direction normal to the plane of said door and to guide said latch elements into said keeper brackets.

3. A sliding door assembly comprising a fixed track extending horizontally across the top of a door opening, trolley means running on said fixed track, a door for closing the door opening, means suspending said door from said trolley means so that the door is movable horizontally along a predetermined path into and out of a closed position in front of and registering with the door opening, said suspending means being operative to impart a vertical downward movement to said door subsequent to the arrival of the latter at said closed position and to impart a vertical upward movement to said door prior to the removal of the latter from its closed position, a bar element disposed adjacent and parallel to each of the leading and trailing vertical edges of said door, at least two link elements pivotally connected to each of said bar elements and the adjacent vertical edge of said door and swingable about axes parallel to the plane of said door so that vertical movement of said door relative to said bar elements is accompanied by relative movement of said door and bar elements in the direction normal to said plane of the door, latch elements projecting rearwardly from said bar elements, sealing means facing forwardly around the door opening, and keeper brackets fixedly disposed at each side of the door opening, said keeper brackets opening to one side to receive said latch elements therein when said door is moved to its closed position and prevent downward movement of said bar elements relative to said keeper brackets so that, when said door is moved vertically downward after arrival at said closed position, said door is displaced rearwardly into

engagement with said sealing means around the door opening.

4. A sliding door assembly according to claim 3; wherein said suspending means includes a member mounted on said door and movable vertically relative to the latter, means for effecting vertical movement of said member pulleys on said door at the opposite sides of said vertically movable member, cables extending around said pulleys and secured at one end to said vertically movable member, and means anchoring the other ends of said cables to said trolley means so that vertical movement of said member effects said vertical movements of said door.

5. A sliding door assembly according to claim 4; wherein said means for effecting vertical movement of said member includes a vertical threaded shaft rotatably mounted on said door for rotation about its longitudinal axis and means for effecting rotation of said shaft in either direction, and said vertically movable member is threaded on said shaft, and including means pre-

venting rotation of said member with said threaded shaft.

6. A sliding door assembly according to claim 5; wherein said means anchoring the other ends of said cables to said trolley means includes a common twin turnbuckle fixed to said trolley means and having said other ends of the cables secured thereto to provide for adjustment of said cables and the levelling of said door.
